METHOD OF MANUFACTURING SOAP

Purdy Bradford, Palos Heights, Ill., assignor to
 Swift & Company, Chicago, Ill., a corporation
 of Illinois

Application June 16, 1947, Serial No. 754,949

2 Claims. (Cl. 260—413)

1

The present invention relates to a method of manufacturing soap. More particularly, the invention has to do with a continuous soap-making process wherein the saponifiable material is subjected to a purification treatment before saponification, whereby the resulting soap is of improved quality and may be employed in the preparation of high-grade toilet soaps.

Important steps in the art of soapmaking involve the selection of the saponifiable raw material and the treatment thereof to produce a soap having the desired characteristics. For example, a high degree of purity, as evidenced by the whiteness of the soap, is highly desirable in high-grade toilet soaps. Crude saponifiable fatty material contains color bodies which, if not removed from the fatty material, are often carried into the finished soap product, thus making it impossible to obtain a high degree of whiteness and purity in the finished product. In producing a superior toilet soap, it is often the practice to select superior raw material relatively color free, and to subject the said material to a bleaching operation before saponification.

The quality of whiteness possessed by the high-grade soap is not only due to the nature of raw material treated, but is also partly due to the soapmaking process employed. When the so-called full-boiled process of making soap is employed, a series of operations are involved, as a result of which the color characteristics of the finished soap are improved. In the full-boiled soap-making process, saponification is carried out in successive stages, which involve boiling of the soap in water, graining or salting out the soap, removing the aqueous layer containing various impurities and glycerine, and settling.

In other soapmaking processes, such as the semi-boiled and cold processes, the operations of boiling, graining and settling are omitted. Consequently, any improvement in color in the finished product due to these omitted operations is lacking. For these reasons, the soap product obtained from the aforesaid soapmaking processes is usually inferior in color characteristics to that obtained from the full-boiled process. Because it is desirable that a high-grade toilet soap possess a high degree of whiteness, the full-boiled process of making soap is generally employed in the manufacture of the superior white soap.

More recently, in the art of soapmaking, there have been developed processes for the continuous saponification of fats. The continuous saponification process generally involves a careful mix-

2

ing of the fat or fatty acids, often in the presence of a diluent with the correct amount of caustic, saponifying the mixture, then spraying the resulting soap into a spray or flash chamber, wherein the volatile products of saponification are flashed off, and the soap is recovered as a dry product.

The washing effects of the various operations of the full-boiled process are lacking in continuous saponification processes. The degree of whiteness in the finished product, therefore, is inferior to that of the full-boiled soap, and is about equivalent to that possessed by the soap obtained by the semi-boiled or cold process.

15 An object of the invention is to produce soap of improved color characteristics, employing a continuous saponification process.

Another object of the invention is to produce soap of improved color characteristics by means 20 of a continuous saponification process, which soap is superior to or equivalent to full-boiled soap.

25 A further object of the invention is to provide a continuous saponification process, wherein purification of the saponifiable fat is continuously effected.

Yet another object of the invention is to provide a continuous saponification process, wherein in the diluent for the fat employed in the continuous saponification of the fat is utilized in the purification of the fat before the continuous saponification thereof.

30 A still further object of the invention is to provide a process wherein the diluent is recovered from the soap, is employed in the purification of the fat, and is simultaneously purified with the fat.

Other objects and advantages of the invention will be apparent from the following description.

40 The invention contemplates broadly a continuous soapmaking process, wherein a solution of the fat to be saponified is effected with the diluent or solvent, such as kerosene, employed in the saponification operations, the resulting 45 solution bleached and then subjected to saponification conditions of temperature and pressure, whereby the fat is converted into soap and glycerine. The products of saponification are then discharged into a vaporization zone maintained under reduced pressure, wherein the volatile materials, including diluent, are separated from the soap by vaporization.

More particularly the invention contemplates forming the fat to be saponified into a solution 50 with the diluent employed in the continuous sa-

saponification of the fat. The solution is treated with a bleaching agent, for example, fuller's earth, at elevated temperatures. After bleaching of the fat solution, the solution is filtered and the earth-free solution mixed with a caustic saponifying reagent. The resulting mixture is charged to a saponification zone to effect the saponification reaction, following which the soap is separated from the volatile products of saponification, including the diluent. The diluent is recycled and is used to form a solution with new fat. The solution is treated with a bleaching agent, whereby both the fat and the recovered solvent may be decolorized.

In carrying out the invention, it is contemplated to employ a continuous saponification process, wherein a diluent is employed for the saponification reagents and the products of saponification. It is also understood that the diluent exhibits solvent action for the fat to be saponified. A suitable saponification process for accomplishing the purposes of the present invention is shown, for example, in Patent No. 2,401,756 to Gunther, issued June 11, 1946.

The aforesaid patent discloses a continuous saponification process, employing a relatively dilute caustic alkali solution and an amount of diluent or solvent for the saponifiable material in excess of 50 per cent, and preferably at least about 75 per cent, based on the saponifiable matter. The relative large amounts of diluent make it possible to effect the saponification reaction at lower temperatures than would be possible were the diluent not present and to maintain the soap product fluid at temperatures below the melting point thereof.

In accordance with the Gunther patent, the caustic alkali solution, saponifiable material, and diluent, formed into an emulsion, are subjected to conditions of saponification in a zone of restricted cross-section, under pressure, to prevent vaporization of any of the reactants and products of saponification. Upon completion of the saponification reaction, the mixture is heated and then sprayed into a low-pressure zone, wherein, by partial pressure distillation, the volatile products of saponification and the diluent are vaporized and continuously removed, leaving the soap product, which may also be continuously removed.

The invention will be more fully understood from the following description read in connection with the accompanying drawing which shows diagrammatically a form of apparatus which can be employed for carrying out the process.

Referring more particularly to the drawing, the numeral 10 indicates a tank for holding saponifiable fat, for example, tallow. Another tank 11 is provided for the storage of the diluent, or solvent, for the fat, such as kerosene. The fat and diluent are introduced through conduits 13 and 14, respectively, into a bleaching tank 16. Bleaching tank 16 may be provided with a hopper 17 for the introduction therein of bleaching material, such as fuller's earth, and means, such as an agitator 18, to effect intimate admixture of the solution and earth. The bleaching tank may also be provided with means for supplying heat to the contents thereof, since it is preferred to carry out the bleaching operation at temperatures above 212° F. Following the bleaching operation, the bleached fat solution is withdrawn from the bleaching tank through line 22 and, in the form of a slurry, is pumped by means of pump 23 into a filter press 25. The filtered fat

solution is collected through line 27 in feed tank 29.

The solution of saponifiable fat in the solvent and aqueous caustic soda of the desired strength held in tank 31 are drawn in the proper ratio through conduits 33 and 35, respectively, by proportioning pump 37, driven by motor 38. From the proportioning pump 37, the saponification reactants flow in a common stream through conduit 40 to homogenizer 41. The homogenizer may be any suitable apparatus wherein the fat solvent solution and the caustic may be thoroughly mixed. A suitable homogenizer may comprise a container and an agitator 43 driven by any suitable source of power through a pulley 44. In the homogenizer an emulsion is formed comprising microscopic globules of caustic soda solution dispersed in the solution of saponifiable material. The emulsion usually contains a soap formed by the instantaneous neutralization of the free fatty acids contained in the fat, which functions to stabilize the dispersion of the aqueous caustic phase in the inert medium.

From the homogenizer the emulsion is pumped by means of pump 46 through conduit 47 into saponification coil 48, which is provided with any suitable heating means to raise the temperature of the emulsified mixture to that necessary for substantially complete saponification. The temperature of reaction will vary inversely with the length of time the mixture remains in the coil, being about 400° F. for a 7-minute reaction period and lower for longer periods of residence in the coil. The pressure in the saponification coil is sufficiently high to prevent substantial evaporation of the diluent. This pressure may be approximately 100 pounds per square inch. Upon completion of the saponification reaction, the fatty mixture passes from the saponification coil through conduit 50 into a relatively short pre-heating coil 52. The temperature of the reaction mixture may be raised in coil 52 high enough, for example, to about 480° F., to supply sufficient sensible heat to facilitate flash evaporation of the inert diluent and glycerine from the soap product when the pressure is reduced. The pressure in the preheating coil is maintained sufficiently high to avoid vaporization which might interfere with keeping the saponification reaction products in a fluid state.

The reaction mixture passes through conduit 54 to a nozzle 56, from which it is continuously sprayed into a vaporizing, or flash, zone 58. The chamber 58 is held at relatively low pressure, preferably less than 40 mm. of mercury absolute, whereby a substantially complete separation of water, glycerine, and other volatiles from the soap product usually occurs. The conditions in the heating coils and flash chamber are preferably controlled so that the temperature of the soap and vapors after flashing is reduced to about 320° F. to 350° F., or to a temperature just above the boiling point of the highest boiling volatile constituent at the existing conditions. In some cases, particularly where it is desired to produce a soap product having a high glycerine content or where glycerine recovery is not material, the pre-heating coil may be eliminated. In the latter case, the reaction mixture passes directly from the saponification coil and through the spray nozzle into the flash chamber. In such cases, more volatile diluent is preferably employed and/or heat supplied through the jacket of the vaporization chamber in order to flash the diluent. The preheating coil is preferred, however,

when it is desired to effect the substantial elimination of glycerine and other volatiles from the soap product in the flash chamber.

Suspended particles of soap settle to the bottom of chamber 58 and are continuously removed by an expeller 60. The expeller may be any suitable type of conveyor for continuously removing the soap while preserving the vacuum in the flash chamber; for example, a screw and shell arrangement which compacts the soap particles as they are advanced by the screw conveyor has been found satisfactory. The soap-free vapors are continuously withdrawn from the top of the flash chamber by means of line 62, and discharged into fractionating column 63. The fractionating column 63, which may be any suitable tower such as a bubble cap type or packed type, is provided with a heating coil 64 and a cooling coil 65.

Fractionating column 63 connects with condenser 68 by means of line 67. The relatively high degree of vacuum is preferably maintained in the fractionating column and condenser 68 to facilitate the continuous withdrawal of volatiles therefrom.

Separation of the different fractions in tower 63 is based on the principles of partial pressure distillation, and therefore temperature conditions in the tower depend on the type of diluent employed and the pressure maintained in the column. In general, the column is held at the reduced pressures which are employed in the flash chamber, that is, less than 40 mm. of mercury absolute and preferably around 20 mm. Thus, when a petroleum fraction having a boiling range between about 450° F. and 500° F. is employed as a diluent, the vapors leaving the top of the column have a temperature within the range of about 100° F. to 120° F., the pressure in the column being about 20 mm., while the temperature of the bottoms in the column, when removing glycerine, may range from about 338° F. to about 368° F. When toluene is the diluent, the temperature of the vapors leaving the top of the column may range from about 59° F. to 79° F., and the temperature of the glycerine about 338° F. to about 368° F., at a reduced pressure of 20 mm. in the column. Sufficient heat is maintained in the column by means of the heating element 64 so that water vapors and the more volatile materials are conveyed to condenser 68. The cooling coil 65 in the upper portion of the fractionating column effects a substantial condensation of the diluent. The condensed solvent is withdrawn from the top section of the column by means of line 70, which may be provided with a draw-off valve 71 to remove the diluent to storage tank, not shown. By appropriate manipulation of valves 71, 72 and 73 the solvent may be recycled to the system through line 74 by means of pump 78 through line 79, or taken to solvent refining unit 81 prior to recycling. In condenser 68 cooling is sufficient to condense the small amount of volatile diluent not condensed in the fractionating column and also water. Volatile materials which remain uncondensed are carried off to vacuum. The condensate from condenser 68 is removed through line 83 to a settling tank 84, wherein a separation of water and solvent into layers of different specific gravities is effected. The water is withdrawn from the settling tank 84 by means of line 86. The solvent may be withdrawn through line 88 and taken to solvent refining unit 81, wherein the solvent may be refined by a countercurrent wash

with caustic and/or acid introduced into the refining unit by aspirator 82. The solvent from settling tank 84 may be recycled to the system by pump 78 after refining or, prior to refining, withdrawn and taken to solvent storage tank, not shown, by means of draw-off valve 90.

The glycerine may be withdrawn from the fractionating column 63 at one or more levels through line 91 and passed through condenser 92 prior to withdrawal thereof in glycerine recovery tank 94, provided with a glycerine outlet 95. Bottoms are withdrawn from the bottom of fractionating column by means of line 98.

The diluent used in the process may be any substance which is substantially inert to the reactants and the products of saponification but which is a solvent for the fat to be saponified. In carrying out the process of the invention, it is preferred to employ an inert, organic hydrocarbon diluent which boils not greatly in excess of about 400° F. at the pressure in the low-pressure zone and which is substantially immiscible with water and the glycerine formed in the reaction, and substantially miscible with the soap at the temperature in the saponification zone. Solvents, such as certain alcohols which are miscible with water and glycerine, may be utilized provided they possess the other requisite physical properties. A preferred inert diluent is a hydrocarbon petroleum fraction which has a boiling range of from 450° F. to 500° F. Other inert diluents which may be employed in the process include kerosene, naptha, gas oil, toluene, and xylene. In some cases noninflammable-type diluents, such as trichlorobenzene or tetrachloroethane, may be used.

The saponifying reagent may consist of any material capable of converting an ester into an alcohol and a salt with the fatty acid, such as caustic soda or caustic potash. The saponifying reagent is preferably a relatively dilute aqueous solution of a concentration of about 50 per cent or less by weight of the caustic.

In accomplishing saponification in the presence of a solvent, it is desirable to employ an amount of solvent equivalent to at least 50 per cent to 75 per cent, and preferably from 100 per cent to 150 per cent by weight of the saponifiable material to provide a highly fluid reaction mixture as formation of the soap product occurs.

Examples of suitable saponifiable materials include animal and vegetable fats and oils, such as tallow and coconut oil, or any organic ester susceptible to saponification. It is understood that the quality of the final soap product will depend to a great extent on the selection of the raw material. Thus, in order to produce a high-grade white toilet soap, it is important to employ saponifiable materials of good quality. However, fats of low quality may also be employed which, because of the bleaching step, may be productive of a soap product having improved qualities of color.

In carrying out the bleaching operation, it has been found that the amount of diluent proposed to be used in the saponification operation, that is, amounts of diluent ranging from about 50 per cent to 150 per cent, based on the saponifiable material, produce satisfactory results. The amount of bleaching agent employed may range from about 0.5 per cent to about 5 per cent, based on the saponifiable material, and may be any suitable bleaching earth or clay or acid-activated clay or activated carbon or charcoal.

The temperatures employed in bleaching the

fat in the presence of the solvent are preferably above 212° F., for example, between about 215° F. and 220° F., in order to evaporate moisture, the presence of which seems to render the bleaching operation less effective. In the absence of water the bleaching step may be accomplished at lower temperatures, a temperature as low as 140° F. having been found satisfactory.

I have found that bleaching of fat in the presence of a solvent prior to charging the resulting bleached solution to a saponification process requiring the presence of a diluent, as hereinabove illustrated, produces a soap of superior color characteristics. The soap produced in this manner may be used in the preparation of high-grade white toilet soaps which heretofore have generally required the full-boiled process for the manufacture thereof. I have found that if the fat is first separately bleached prior to being formed into a mixture with the diluent and then saponified, the resulting soap does not possess the degree of whiteness characteristic of soap produced by the full-boiled process or the process herein disclosed.

In soapmaking processes heretofore practiced it has not been customary to bleach a solution of the fat, for such a process used in connection therewith would have no particular utility. For example, if the aforesaid process were applied to the full-boiled process of soap manufacture, the solvent would require removal after the bleaching operation, an expensive operation and one which would tend to discolor the fat, thus rendering the whole operation useless. For these reasons, bleaching of the fat has heretofore been accomplished in the absence of a solvent.

In accordance with the present invention, however, the bleaching of the fat in the presence of the diluent employed in the continuous saponification process has many advantages. For example, the heat imparted to the fat in effecting the solution thereof may be advantageously utilized in the saponification reaction. In addition, by virtue of the combination of the bleaching step with the steps in the continuous saponification process, it is not required to remove the solvent after bleaching. The solvent is removed after saponification from the soap, an operation which is inherent in the continuous saponification process. For this reason no discoloration of the fat occurs through distillation of the solvent therefrom, and the process is rendered economical. By using fat immediately after decolorizing and without removing solvent there is no opportunity for fat to deteriorate and a better colored soap is obtained. Moreover, I have found that the solvent distilled from the products of the saponification reaction is often discolored, but that in reusing the solvent in the bleaching of additional fat, the solvent is decolorized along with the fat and may thus be used indefinitely.

As an example of the invention, 100 parts of prime tallow, not darker than 17 F. A. C., having a free fatty acid content of 2.5 per cent, and 125 parts of a petroleum fraction boiling between about 450° F. and 500° F. were formed into a solution. The solution was then agitated in the presence of about 1 per cent fuller's earth for about one-half hour and at a temperature of about 215° F. to bleach the fat. Following the bleaching operation, the mixture was filtered and the resultant earth-free solution was formed into a common stream with a 50 per cent caustic solution in the ratio of 28 parts of the caustic to 100 parts of fat. The fat solution and caustic were inti-

mately mixed in the homogenizer to form an emulsion. The emulsion was continuously passed through a saponification coil at a temperature of about 415° F., under a pressure of about 100 pounds per square inch. The time of flow of the reaction mixture through the saponification coil was about seven minutes, after which time the saponification reaction was completed. Following saponification, the mixture was passed through a preheating coil and the temperature thereof raised to about 480° F. in about 25 seconds, while maintaining the pressure of about 100 pounds per square inch. The mixture was then sprayed through a restricted nozzle into the flash chamber, which was maintained at about 400° F. and at a reduced pressure of about 20 mm. of mercury absolute. Solid soap in the form of a white powder settled to the bottom of the flash chamber and was continuously removed therefrom. The vapors were continuously discharged into a fractionating tower, also maintained at a pressure of about 20 mm., wherein the vapors were separated by rectification. The temperature of the vapors coming off the top of the tower was about 100° F., at which temperature the major portion of the solvent condensed as a reflux condensate and was taken off of an upper plate of the column and recycled to the system. The volatile materials, including the small proportion of uncondensed diluent, passed into a condenser, wherein water and the diluent were condensed and separated by stratification in a settling tank.

Employing portions of the same tallow used in accordance with the foregoing process, saponification of one portion of the tallow was effected by following the full-boiled process, and the other portion according to a continuous process, substantially as hereinabove described, except that bleaching of the tallow was effected in the absence of solvent. Three 40-gram samples of soap, representing each of the three methods, were separately dissolved in 100 ml. of specially denatured ethyl alcohol, and the three solutions measured for color on the Lovibond scale. Soap from the continuous process, wherein bleaching was performed without the solvent, gave a reading of 2.3 R., while the full-boiled soap gave a value of 1.2 R., and soap prepared in accordance with the present invention, 1.0 R. The results show that the present invention is productive of a soap of a higher degree of whiteness than soap prepared by prior art methods.

As another illustrative example of the invention, a second lot of tallow was substituted for the fat used in the preceding example. Bleaching and saponification conditions were the same as in the first example. Color tests were then performed by comparing, for color, the alcohol solution of the resulting soap with the solutions of soap made from portions of the same tallow by the full-boiled process and the continuous soap process wherein the tallow had not been bleached in the presence of the diluent. The colors of the three solutions were as follows: 3.6 R. for soap obtained by the continuous process wherein bleaching of the fat was effected in the absence of solvent; 2.6 R. for full-boiled soap, and 2.5 R. for soap obtained in accordance with the invention.

While the present invention has been described as being particularly adapted to the soapmaking process described in the Gunther patent aforementioned, it is understood that the invention is not to be construed as being limited thereto, but may be applied to other soapmaking

processes embodying various modifications, and which employ a diluent for the saponification reactants and reaction products. For example, the invention may be used in connection with continuous saponification processes which employ substantially smaller amounts of diluent than are disclosed in the Gunther patent or with processes which are characterized by the use of an anhydrous saponifying reagent and a diluent.

Obviously, many modifications and variations of the invention, as hereinbefore set forth, may be made without departing from the spirit and scope thereof, and therefore only such limitations should be imposed as are indicated in the appended claims.

I claim:

1. In a continuous process of manufacturing soap, the improvement which comprises: forming an intimate mixture of a saponifiable material containing objectionable color bodies, a solid adsorbent bleaching agent, and an inert hydrocarbon boiling between about 230° and 500° F., said hydrocarbon having a property of forming a solution with both the saponifiable material and the soap subsequently formed therefrom; separating the bleaching agent and objectionable color bodies from the solution of saponifiable material; subjecting the bleached saponifiable material while dissolved in the said hydrocarbon to a saponification temperature and pressure in the presence of an alkaline saponification reagent to convert the saponifiable material into glycerin and soap, said soap substantially free of objectionable color bodies being dissolved in said hydrocarbon; and discharging the products of saponification and the hydrocarbon into a fractionation zone to individually recover the said products of saponification and the hydrocarbon.

2. In a continuous process of manufacturing soap, the improvement which comprises: forming in a mixing zone an intimate mixture of a saponifiable material containing objectionable

color bodies, a solid adsorbent bleaching agent and an inert hydrocarbon boiling between about 230° and 500° F., said hydrocarbon having the property of forming a solution with both the saponifiable material and the soap subsequently formed therefrom, and being present in an amount at least between 100 and 150 per cent by weight of the saponifiable material; separating the bleaching agent and objectionable color bodies from the solution of saponifiable material; subjecting the bleached saponifiable material while dissolved in the said hydrocarbon to a saponification temperature and pressure in the presence of an alkaline saponification reagent to convert the saponifiable material into glycerin and soap, said soap substantially free of objectionable color bodies being dissolved in the said hydrocarbon; discharging the products of saponification including dissolved soap, glycerin, and hydrocarbon into a fractionation zone maintained at subatmospheric pressure to individually separate the soap, glycerin, and hydrocarbon; and recycling the said hydrocarbon without further processing to the mixing zone where it is bleached simultaneously with the saponifiable material.
